(57) **CLAIM**

The ornamental design for a plumbing fitting, as shown and described.

DESCRIPTION

FIG. 1 is a top, left, front perspective view of a plumbing fitting showing our new design;

FIG. 2 is a left side elevational view thereof, the right side elevational view thereof being a mirror image of the left side shown;

FIG. 3 is a front elevational view thereof;

FIG. 4 is a rear elevational view thereof;

FIG. 5 is a top plan view thereof; and,

FIG. 6 is a bottom plan view thereof.

The broken line representations in the figures show unclaimed environment, and thus form no part of the claimed design.

The nature of this product is a plumbing fitting, such as a spout for a sensor activated faucet.
